UNITED STATES PATENT OFFICE

ARTHUR F. PYM, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY

LASTING MACHINE

Application filed April 15, 1930. Serial No. 444,560.

This invention relates to machines for use in the manufacture of shoes for lasting the upper materials. While the invention is herein illustrated as applied to means for lasting the toe end of a shoe, it is to be understood that in its more general aspects it is not limited to means for operating upon that particular portion of a shoe, but is applicable, for example, to means for lasting the heel end.

In the operation of lasting machines having wiping means or wipers used both to wipe the upper heightwise of the shoe, i. e., to effect what is termed the upwiping operation, and also to wipe it inwardly over the shoe bottom, it is important to terminate the relative upwiping movement of the wiping means and the shoe with the wiping means in proper relation to the shoe bottom to begin the overwiping operation, in order to apply effective pressure to the upper in wiping it about the edge of the shoe bottom without losing control of it between the upwiping and overwiping operations. Manually operated bed-lasting machines usually include in their organization a hand lever for advancing and closing the toe wipers about the toe of the shoe and for holding them pressed against the upper in the upwiping operation, and a treadle for moving the wipers heightwise of the toe while they are thus held against the upper. In determining when to stop the upwiping operation in the use of such a machine the operator must rely principally upon the decrease of resistance to the advancing and closing movement of the wipers which he perceives through the hand lever as the wipers are carried by the treadle past the edge of the shoe bottom. Proper coordination of the upwiping and overwiping operations in such manner as to wipe the upper smoothly and tightly about the edge of the shoe bottom without loss of the tension applied to the upper in the upwiping operation therefore requires the exercise of much care and skill.

In view of the above and other considerations, it is an object of this invention to provide an organization whereby the relation between a shoe and the lasting means or wipers is controlled in such manner as to re-

lieve the operator of a manually operated machine of the necessity for exercising the care required heretofore in the transition between the upwiping operation and the overwiping operation, and in general also to accomplish improved results in the lasting operation without the use of complicated mechanism for determining the relation between the lasting means and the shoe, whether the lasting machine be operated manually or by power. For the purposes in view the invention accordingly provides a novel construction and arrangement of means for effecting relative movement of a shoe and lasting or wiping means in such manner as to insure effective control of the upper throughout the lasting operation. The machine herein shown has toe-embracing wipers mounted for advancing and closing movement about the toe of the shoe and also for movement heightwise of the shoe as heretofore, together with wiper-operating mechanism so constructed as to have a constant tendency in operation to impart both movements to the wipers, but controlled by the resistances to the two movements in such manner that the upwiping operation and the overwiping operation are effected in a sequence determined by the shoe. As illustrated, the construction is such that the resistance to the movement of the wipers heightwise of the shoe is normally greater than the resistance to their advancing and closing movement, so that the operating mechanism is effective first to advance and close the wipers about the toe of the shoe, then to move them heightwise of the shoe in response to the resistance of the shoe to their further advancing and closing movement, and then to force them inwardly over the shoe bottom while maintaining them firmly pressed against the upper as soon as they pass the edge of the shoe bottom. More particularly, the wiper-operating mechanism herein shown comprises a floating lever connected at its opposite ends to the wipers for imparting to them respectively their upwiping movement and their advancing and closing movement, and means for applying force to the lever between its opposite ends to oper-

ate it. In accordance with a further feature also there is provided in the combination additional means for controlling the pressure of the wiping means on the shoe bottom, the construction shown comprising a treadle whereby the operator is enabled to move the wipers heightwise of the shoe to increase their pressure upon the shoe bottom and also to relieve their pressure on the shoe when it is desired to withdraw them from the shoe.

10 The novel features of the invention, including various novel details of construction and combinations of parts, will now be more particularly described by reference to the 15 accompanying drawings and thereafter pointed out in the claims.

In the drawings,

Fig. 1 is a view in front elevation of a machine in which the invention is embodied;

20 Fig. 2 is a plan view, with portions of the structure broken away;

Fig. 3 is a view in left-hand end elevation of portions of the mechanism provided for purposes of this invention; and

25 Figs. 4 and 5 are sectional views illustrating the positions of the toe wipers at different times in the lasting operation.

The invention is herein illustrated as embodied in a toe-lasting machine which is in 30 many respects of the same construction as disclosed in a copending application of F. N. LaChapelle and F. C. Eastman, Serial No. 430,071, filed on February 20, 1930. Only such portions of the machine, therefore, as 35 it is necessary to refer to for an understanding of the invention will be herein described in detail.

The last and its shoe materials are positioned for the toe-lasting operation by means 40 of three pins 10 which project through holes in the insole into sockets in the last in the same manner as disclosed in Letters Patent No. 1,674,060, granted on June 19, 1928, upon an earlier application of mine. The pins 10 45 are mounted on a plate 12 which is fast on a stationary arm 14, and the last and shoe are supported in the position determined by the pins by a toe rest 16 which is moved upwardly against the shoe and is locked in supporting 50 position in the manner disclosed in the above-mentioned application. For wiping the toe-end portion of the upper into lasted position the machine is provided with toe-embracing wipers 18 which are supported on a wiper 55 holder 20 adjustably mounted on a slide 22 which is horizontally movable lengthwise of the shoe upon the head of another slide 24 vertically movable in guideways in the frame 60 of the machine. The slide 22 is moved to carry the wipers preliminarily toward the shoe from an initial retracted position by means of a power operated cam 26 which acts on a lever 28 connected to the slide. The vertically movable slide 24 is connected substantially as heretofore by a link 30 to a crank

70 arm 32 fast on a rock shaft 34 upon which is secured a double-acting treadle 36 whereby the operator is enabled to press the wipers 18 down upon the shoe bottom and to raise them from the shoe bottom, the slide 24 in the construction herein shown being movable to effect the upwiping operation through the action of mechanism more particularly hereinafter described. For advancing and closing the wipers about the toe the machine is 75 provided, as heretofore, with a plunger 38 connected by a cross bar 40 and links 42 to wiper carriers 44 on which the wipers are secured, the wiper carriers being guided by rolls 46 and 48 and cam slots 50 and 52 (Fig. 2) to swing the wipers about a vertical axis 80 and thus to close them laterally of the shoe as they are advanced lengthwise of the shoe.

For operating the slide 24 and the plunger 38 to impart to the wipers their upwiping movement and their advancing and closing movement, the machine is provided, for purposes of this invention, with wiper-operating mechanism including a floating lever 54, i. e., a lever having no fixed fulcrum. This lever is connected at one end to the link 30 through which the slide 24 is operated, this link being provided with a coupling member 56 having a recess into which the end of the lever extends and having in its opposite sides slots 95 to receive a pin 58 carried by the lever. At its opposite end the lever 54 is connected by a link 60 to a bell-crank lever 62 fast on a rock shaft 64 supported by a bracket 66 on the frame of the machine, the upper end of the bell-crank lever being connected to a block 68 which is fast on the outer end of the plunger 38. In order to clear portions of the machine which are directly below the plunger 38, the lever 62 is made double, the two parts being secured to the rock shaft 64 and extending upwardly at opposite sides of the plunger 38 and having at their upper ends vertical slots 70 in which are mounted rolls 72 carried by a cross bar 74 which is connected centrally to the block 68 by means of a pivot stud 76. It will be understood that through the provision of the slots 70 operative relation is maintained between the bell-crank lever 62 and the plunger 38 in all positions of vertical movement of the slide 24 and the wipers 18. For operating the floating lever 54 there is provided, in the machine herein shown, a hand lever 78 which is fast on a rock shaft 80 mounted in the bracket 66, this rock shaft having fast thereon a double lever 82 the two arms of which are connected by a web 83 and extend along the opposite sides of the lever 54, these arms being connected to the lever 54 by a pin 84. As illustrated in Fig. 1, the pin 84 may be inserted in any one of a number of holes 86 in the lever 54 and corresponding alined holes 88 in the two arms of the lever 82 to vary the ratio 130

between the effective forces applied by the lever 54 to the slide 24 and the plunger 38.

It will thus be seen that by swinging movement of the hand lever 78 upwardly directed force is applied to the floating lever 54 between its opposite ends, and that the lever 54 when thus operated tends constantly both to raise the slide 24 to impart to the wipers 18 upwiping movement and also to operate the plunger 38 to impart to the wipers advancing and closing movement. The construction, however, is such that there is normally greater resistance to the upward movement of the slide 24 than to the movement 15 of the plunger 38, this being due to the weight of the slide and of the parts supported thereon and also, in the construction shown, to springs 90 (only one of which is shown), these springs being anchored at their lower 20 ends to the frame of the machine and connected at their upper ends to a cross bar 92 which bears downwardly on the slide 22. As a result of this resistance to the upward movement of the slide 24 the lever 54 is effective first, by swinging movement about its connection with the coupling member 56, to advance and close the wipers 18 about the toe of the shoe, the arrangement being such that the wipers thus engage the shoe in a 25 location below the edge of the shoe bottom as illustrated in Figs. 1 and 4. In response to resistance of the shoe to further advancing and closing movement of the wipers the lever 54 then swings about its connection with the 30 link 60 to lift the slide 24 and thus to impart upwiping movement to the wipers while the latter are held in firm engagement with the upper by reason of the force applied simultaneously through the lever to the plunger 38. As soon as the wipers in their upwiping 35 movement pass the edge of the shoe bottom the decrease in the resistance to their advancing and closing movement, whereby this resistance becomes less than the resistance to 40 their upward movement, causes them to be forced inwardly over the shoe bottom by the action of the lever 54 on the plunger 38 while they are held firmly pressed against the upper by the force of the springs 90 and the 45 weight of the slide 24 and the parts thereon. It will thus be seen that the wiper-operating mechanism, while tending constantly to impart to the wipers both upward movement and advancing and closing movement, is controlled at all times by the resistances to these 50 movements, so that the upwiping and overwiping movements are effected in a sequence determined by the shoe while the wipers are maintained continuously in firm engagement 55 with the upper. Insurance is thus afforded that the upper will be wiped smoothly and tightly inward over the edge of the shoe bottom.

The manner of operation of the machine 60 will be readily understood from the foregoing

description. All that the operator has to do in performing the upwiping and overwiping operations is to swing the hand lever 78 in one direction, without the necessity of giving any thought to the transition from the upwiping operation to the overwiping operation. During the overwiping operation, or after the completion of that operation, the operator may, if desired, increase the downward pressure of the wipers on the upper by use of the treadle 36, and also by use of the treadle he may raise the wipers to relieve the pressure on the upper when the lever 78 is moved reversely to withdraw the wipers from the shoe and may further control them by the treadle in their downward movement to starting position. After the upwiping and overwiping operations have been performed in the manner described they may, if desired, be repeated in the same manner as before, and in the second overwiping operation the wipers may be stopped in a position such as to permit fastenings to be driven to fasten the margin of the upper to the insole while the upper is held by the wipers.

While the invention is herein illustrated as applied to a manually operated lasting machine, it will be recognized that it provides simple and effective means for insuring the proper relation between lasting means and a shoe which is likewise applicable to power-operated or automatic machines. It is also to be understood that the invention in its more general aspects is not limited with respect to the character of the form over which the upper is shaped, and the term "lasting" as used herein is accordingly not intended, unless required by the context, to imply any limitation in this respect.

Having described the invention, what I claim as new and desire to secure by Letters Patent of the United States is:

1. In a lasting machine, the combination with a shoe support and end-lasting wipers mounted for relative movement heightwise of a shoe in a direction to upwipe the upper, the wipers being mounted also for advancing and closing movement about an end of the shoe, of operating mechanism so constructed as to have a constant tendency in operation to effect both said movements, said operating mechanism being movable under control of the resistances to both said movements first to advance and close the wipers about the end of the shoe, then to effect relative movement of the shoe support and the wipers to wipe the upper heightwise of the shoe, and then to force the wipers inwardly over the bottom of the shoe.

2. In a lasting machine, the combination with end-lasting wipers mounted for advancing and closing movement about an end of a shoe and also for movement heightwise of the shoe in a direction to upwipe the upper,

of operating mechanism so constructed as to have a constant tendency in operation to impart both said movements to the wipers, said operating mechanism being movable under 5 control of the resistances to the two movements of the wipers first to advance and close the wipers about the end of the shoe, then to move them heightwise of the shoe to wipe the upper toward the edge of the shoe bottom 10 in response to resistance of the shoe to their further advancing and closing movement, and then to force them inwardly over the shoe bottom in response to the decrease in the resistance to their advancing and closing movement as they pass the edge of the shoe bottom. 15

3. In a lasting machine, the combination with end-lasting wipers mounted for advancing and closing movement about an end of a shoe and also for movement heightwise of 20 the shoe in a direction to upwipe the upper, of operating mechanism so constructed as to have a constant tendency in operation to impart both said movements to the wipers but controlled throughout its operation by the 25 resistances to the different movements, the construction being such that the resistance to the movement of the wipers heightwise of the shoe is normally greater than the resistance to their advancing and closing movement to cause them to be advanced and closed 30 about the end of the shoe prior to their movement heightwise of the shoe and to be further advanced and closed as soon as they pass the edge of the shoe bottom in said last-mentioned movement. 35

4. In a lasting machine, the combination with end-lasting wipers mounted for advancing and closing movement about an end of a shoe and also for upwiping movement heightwise of the shoe, of operating mechanism having different connections with said wipers for imparting to them respectively their different movements, said operating mechanism being movable as determined by the resistances to the 40 different movements of the wipers to impart to them their upwiping movement in response to resistance of the shoe to their advancing and closing movement and to force them inwardly over the shoe bottom in response to the decrease in the resistance to their 45 advancing and closing movement as soon as they pass the edge of the shoe bottom. 50

5. In a lasting machine, the combination with end-lasting wipers mounted for advancing and closing movement about an end of a shoe and also for upwiping movement heightwise of the shoe, of operating mechanism having different connections with said wipers for imparting to them respectively their different movements, said operating mechanism being movable as determined by the resistances to the different movements of the wipers to impart to them each movement in response to the resistance to the other movement, and spring means for increasing the 55

resistance to the upwiping movement of the wipers to cause them to be pressed firmly against the shoe by the operating mechanism during that movement. 60

6. In a lasting machine, the combination 70 with a shoe support and end-lasting wipers mounted for relative movement heightwise of a shoe in a direction to upwipe the upper, said wipers being mounted also for advancing and closing movement about an end of the shoe, of operating means comprising a member arranged to act through different trains of mechanism respectively to effect said relative movement and said advancing and closing movement, said member being movable as 75 determined by the resistances to both said movements to effect the relative movement of the shoe support and the wipers heightwise of the shoe in response to resistance of the shoe to the advancing and closing movement 80 of the wipers and to force the wipers inwardly over the shoe bottom in response to the decrease in the resistance to their advancing and closing movement when they are past the edge of the shoe bottom. 85

7. In a lasting machine, the combination 90 with a shoe support and end-lasting wipers mounted for relative movement heightwise of a shoe in a direction to upwipe the upper, said wipers being mounted also for advancing and closing movement about an end of the shoe, of operating means comprising a floating lever arranged to effect both said relative movement and said advancing and closing movement under control of the resistances to said different movements. 95

8. In a lasting machine, the combination 100 with end-lasting wipers mounted for advancing and closing movement about an end of a shoe and also for upwiping movement heightwise of the shoe, of operating means comprising a member arranged to act through different trains of mechanism respectively to impart to the wipers their different movements, said member being movable under 105 control of the resistances to the different movements of the wipers to impart to them upwiping movement and movement inwardly over the shoe bottom in a sequence determined by the shoe. 110

9. In a lasting machine, the combination 115 with end-lasting wipers mounted for advancing and closing movement about an end of a shoe and also for upwiping movement heightwise of the shoe, of operating means comprising a member arranged to act through different trains of mechanism respectively to impart to the wipers their different movements, said member being movable under control of the resistances to the different 120 movements of the wipers to impart to them upwiping movement and movement inwardly over the shoe bottom in a sequence determined by the shoe, and means for varying the 125 ratio between the forces applied by said mem- 130

ber through the different trains of mechanism.

10. In a lasting machine, the combination with end-lasting wipers mounted for advancing and closing movement about an end of a shoe and also for upwiping movement heightwise of the shoe, of operating means comprising a floating lever arranged to act through different trains of mechanism respectively to impart to the wipers their different movements, said lever being movable under control of the resistances to the different movements of the wipers to impart to them each movement in response to the resistance to the other movement.

11. In a lasting machine, the combination with end-lasting wipers mounted for advancing and closing movement about an end of a shoe and also for upwiping movement heightwise of the shoe, of operating means comprising a floating lever arranged to act through different trains of mechanism respectively to impart to the wipers their different movements, said lever being movable under control of the resistances to the different movements of the wipers to impart to them each movement in response to the resistance to the other movement, and spring means arranged to increase the resistance to the upwiping movement relatively to the resistance to the other movement.

12. In a lasting machine, the combination with end-lasting wipers mounted for advancing and closing movement about an end of a shoe and also for upwiping movement heightwise of the shoe, of operating means comprising a lever connected through different trains of mechanism to said wipers for imparting to them their different movements, said lever being arranged to fulcrum about its connection with each train of mechanism to operate the wipers through the other train of mechanism and being controlled in its movements by the resistances to the different movements of the wipers.

13. In a lasting machine, the combination with end-lasting wipers mounted for advancing and closing movement about an end of a shoe and also for upwiping movement heightwise of the shoe, of operating mechanism comprising a floating lever arranged to act at different portions of its length respectively to impart to said wipers their different movements, and means for applying force to said lever at another portion of its length to operate it.

14. In a lasting machine, the combination with end-lasting wipers mounted for advancing and closing movement about an end of a shoe and also for upwiping movement heightwise of the shoe, of operating mechanism comprising a floating lever connected at its opposite ends respectively to the wipers for imparting to them their different

movements, and means for applying force to said lever between its ends to operate it.

15. In a lasting machine, the combination with end-lasting wipers mounted for advancing and closing movement about an end of a shoe and also for upwiping movement heightwise of the shoe, of operating mechanism comprising a floating lever having connections at its opposite ends for imparting to the wipers their different movements respectively, and means for applying force to said lever between its ends to operate it, the point of application of said force being adjustable to vary the ratio between the effective forces applied to the different connections.

16. In a lasting machine, the combination with end-lasting wipers mounted for advancing and closing movement about an end of a shoe, of a wiper holder movable upwardly to raise the wipers in operating on the shoe, and operating mechanism so constructed as to have a constant tendency in operation both to advance and close the wipers and to raise the wiper holder, said operating mechanism being movable under control of the resistances to the advancing and closing of the wipers and to the raising of the wiper holder to impart to the wipers upwiping movement and movement inwardly over the shoe bottom in a sequence determined by the shoe.

17. In a lasting machine, the combination with end-lasting wipers mounted for advancing and closing movement about an end of a shoe, of a wiper holder movable upwardly to raise the wipers in operating on the shoe, and operating mechanism comprising a member having different connections with the wipers and with the wiper holder for imparting respectively advancing and closing movement to the wipers and upward movement to the wiper holder under control of the resistances to those different movements, the construction being such that the resistance to the upward movement of the wiper holder is greater than the resistance to the advancing and closing movement of the wipers when the wipers are not in contact with the shoe.

18. In a lasting machine, the combination with end-lasting wipers, of a wiper holder movable upwardly to raise the wipers in operating on a shoe, mechanism movable with said wiper holder for advancing and closing the wipers, a floating lever connected at one portion of its length to said wiper holder for raising it, means connecting the lever at another portion of its length to the wiper advancing and closing mechanism, and means for applying force to said lever to operate it.

19. In a lasting machine, the combination with end-lasting wipers, of a wiper holder movable upwardly to raise the wipers in operating on a shoe, mechanism movable with

said wiper holder for advancing and closing the wipers, a floating lever connected at one end to said wiper holder for raising it, operating connections between the other end of said lever and the wiper advancing and closing mechanism, and a hand lever connected to said floating lever between the ends of the latter for imparting operative movement thereto.

10 20. In a lasting machine, the combination with endl-lasting wipers, of a wiper holder movable upwardly to raise the wipers in operating on a shoe, mechanism including a plunger carried by said wiper holder for advancing and closing the wipers, a floating lever connected at one portion of its length to said wiper holder for raising it, mechanism comprising a link and a bell-crank lever for connecting said floating lever at another 15 portion of its length to said plunger, and means connected to said floating lever at another portion of its length for operating it.

25 30. In a lasting machine, the combination with end-lasting wipers mounted for advancing and closing movement about an end of a shoe and also for movement heightwise of the shoe in a direction to upwipe the upper, of operating mechanism so constructed as to have a constant tendency in operation to impart both said movements to the wipers, said operating mechanism being movable as determined by the resistances to the different movements of the wipers to impart to them upwiping movement heightwise of the shoe 35 in response to resistance of the shoe to their advancing and closing movement and to force them inwardly over the shoe bottom in response to the decrease in the resistance to their advancing and closing movement as soon as they pass the edge of the shoe bottom, and means movable to increase the pressure of the wipers on the shoe when they are over the shoe bottom.

40 45. In a lasting machine, the combination with end-lasting wipers mounted for advancing and closing movement about an end of a shoe and also for movement heightwise of the shoe in a direction to upwipe the upper, of operating mechanism comprising a member arranged to act through different connections respectively to impart to the wipers said different movements, said member being movable as determined by the resistances to the different movements of the wipers to impart to them upwiping movement and movement inwardly over the shoe bottom, and additional mechanism movable to vary the pressure of the wipers on the shoe when they are over the shoe bottom.

50 55. In a lasting machine, the combination with end-lasting wipers mounted for advancing and closing movement about an end of a shoe and also for movement heightwise of the shoe in a direction to upwipe the upper, of operating mechanism so constructed as to

have a constant tendency in operation to impart both said movements to the wipers, said operating mechanism being movable as determined by the resistances to the different movements of the wipers to impart to them upwiping movement heightwise of the shoe in response to resistance of the shoe to their advancing and closing movement and to force them inwardly over the shoe bottom in response to the decrease in the resistance to their advancing and closing movement as soon as they pass the edge of the shoe bottom, and mechanism constructed to enable the operator to control at will the pressure of the wipers on the shoe in the course of their operation on the shoe bottom.

60 65. In a lasting machine, the combination with end-lasting wipers mounted for advancing and closing movement about an end of a shoe, of a wiper holder movable upwardly and downwardly to raise and lower the wipers in operating on the shoe, operating mechanism so constructed as to have a constant tendency in operation both to advance and close the wipers and to raise the wiper holder, said operating mechanism being movable as determined by the resistances to the advancing and closing of the wipers and to the raising of the wiper holder to impart to the wipers upwiping movement and movement inwardly over the shoe bottom in a sequence determined by the shoe, and treadle mechanism constructed to enable the operator to press the wipers downwardly upon the shoe bottom at will and also to raise them above the shoe bottom preparatory to their withdrawal from over the shoe.

70 75. In a lasting machine, the combination with a shoe support and wiping means mounted for relative movement heightwise of a shoe in a direction to upwipe the upper and for relative movement in a direction transverse to the height of the shoe, of operating mechanism so constructed as to have a constant tendency in operation to effect both said relative movements, said operating mechanism being movable under control of the resistances to said relative movements to cause the wiping means first to wipe the upper heightwise of the shoe and then to wipe it inwardly over the shoe bottom.

80 85. In a lasting machine, the combination with a wiping means mounted for movement heightwise of a shoe in a direction to upwipe the upper and also for movement in a direction transverse to the height of the shoe, of operating mechanism so constructed as to have a constant tendency in operation to impart both said movements to the wiping means but differently movable as determined by the resistances to said different movements to force the wiping means into engagement with the shoe at a distance from the edge of the shoe bottom, then to move it heightwise of the shoe to the edge of the shoe bottom,

and thereafter to force it inwardly over the shoe bottom.

27. In a lasting machine, the combination with a wiping means mounted for upwiping movement heightwise of a shoe and also for movement in a direction transverse to the height of the shoe to engage the shoe prior to the upwiping operation and to wipe the upper inwardly over the shoe bottom after that operation, of operating mechanism so constructed as to have a constant tendency in operation to impart movements in both directions to said wiping means but operative to effect the different movements under control of the resistances to said movements, the construction being such that the resistance to the movement heightwise of the shoe is normally greater than the resistance to the movement in the other direction to cause the wiping means to be carried into engagement with the shoe prior to its upwiping movement and to be maintained in firm engagement with the upper during that movement and its movement inwardly over the edge of the shoe bottom.

28. In a lasting machine, the combination with wiping means mounted for upwiping movement heightwise of a shoe to wipe the upper toward the edge of the shoe bottom and for inward movement with respect to the shoe to wipe it over the shoe bottom, of operating mechanism so constructed as to have a constant tendency in operation to impart both said movements to the wiping means but controlled by the shoe to effect the upwiping movement in response to resistance of the shoe to the inward movement and to effect the latter movement in response to the decrease in the resistance to that movement as the wiping means passes the edge of the shoe bottom.

29. In a lasting machine, the combination with wiping means mounted for upwiping movement heightwise of a shoe to wipe the upper toward the edge of the shoe bottom and for inward movement with respect to the shoe to press on the upper in the upwiping operation and then to wipe it over the shoe bottom, of operating mechanism so constructed as to have a constant tendency in operation to impart both said movements to the wiping means but operative to effect said movements as determined by the resistances to the different movements, the construction being such that except for the resistance of the shoe to the inward movement of the wiping means the resistance to the upwiping movement is greater than the resistance to the inward movement to cause said operating mechanism to press the wiping means firmly against the upper in the upwiping operation.

30. In a lasting machine, the combination with a wiping means mounted for upwiping movement heightwise of a shoe to wipe the upper toward the edge of the shoe bottom and for inward movement with respect to the shoe

to wipe it over the shoe bottom, of operating mechanism having different connections to said wiping means for imparting to said means respectively its different movements, said operating mechanism being constructed to effect the upwiping movement in response to resistance of the shoe to inward movement of the wiping means and to effect the inward movement over the shoe bottom in response to the decrease in the resistance to that movement as the wiping means passes the edge of the shoe bottom.

31. In a lasting machine, the combination with a wiping means mounted for upwiping movement heightwise of a shoe to wipe the upper toward the edge of the shoe bottom and for inward movement with respect to the shoe to wipe it over the shoe bottom, of operating mechanism comprising a member arranged to act through different trains of mechanism respectively to impart to said wiping means its different movements, said member being controlled by the shoe to effect the upwiping movement in response to resistance of the shoe to the inward movement and to effect the latter movement in response to the decrease in the resistance to that movement as the wiping means passes the edge of the shoe bottom.

32. In a lasting machine, the combination with wiping means mounted for upwiping movement heightwise of a shoe to wipe the upper toward the edge of the shoe bottom and for inward movement with respect to the shoe to wipe it over the shoe bottom, of operating mechanism comprising a floating lever connected at different portions of its length respectively to the wiping means for imparting to said means the different movements, and means for applying force to the lever at another portion of its length to operate it, said lever being controlled by the shoe to effect the upwiping movement in response to resistance of the shoe to the inward movement of the wiping means and to effect the latter movement in response to the decrease in the resistance to that movement as the wiping means passes the edge of the shoe bottom.

33. In a lasting machine, the combination with a wiping means, of operating mechanism comprising a member having different connections to said wiping means for moving said means respectively into engagement with a shoe at a distance from the edge of the shoe bottom and heightwise of the shoe to upwipe the upper, said member being movable first to engage the wiping means with the shoe and then movable in response to such engagement to impart to the wiping means its upwiping movement.

34. In a lasting machine, the combination with wiping means, of operating mechanism comprising a lever movable about one fulcrum to force said wiping means into en-

gagement with a shoe at a distance from the edge of the shoe bottom and movable about a different fulcrum in response to such engagement to impart to the wiping means unwiping movement heightwise of the shoe.

35. In a lasting machine, the combination with wiping means, of operating means comprising a member arranged to act through one train of mechanism to move said wiping means into engagement with a shoe at a distance from the edge of the shoe bottom and through another train of mechanism to move said wiping means heightwise of the shoe to upwipe the upper, said member being so controlled as to operate the last-mentioned train of mechanism in response to resistance of the shoe to movement of the first train of mechanism.

36. In a lasting machine, the combination with wiping means, of operating means comprising a lever connected through one train of mechanism to said wiping means to move said means into engagement with a shoe at a distance from the edge of the shoe bottom and connected through another train of mechanism to the wiping means to move said means heightwise of the shoe to upwipe the upper, said lever being arranged to fulcrum about its connection with said first-mentioned train of mechanism to operate the other train of mechanism.

37. In a lasting machine, the combination with a wiping means mounted for upwiping movement heightwise of a shoe to wipe the upper toward the edge of the shoe bottom and for inward movement with respect to the shoe to wipe it over the shoe bottom, of operating mechanism so constructed as to have a constant tendency in operation to impart both said movements to the wiping means, said operating mechanism being movable as determined by the resistances to the different movements of the wiping means to impart to said means its upwiping movement and then its movement inwardly over the shoe bottom, and mechanism movable to increase the pressure of the wiping means on the shoe when it is over the shoe bottom.

38. In a lasting machine, the combination with a wiping means mounted for upwiping movement heightwise of a shoe to wipe the upper toward the edge of the shoe bottom and for inward movement with respect to the shoe to wipe it over the shoe bottom, of operating mechanism comprising a member arranged to act through different connections respectively to impart to said wiping means its different movements, said member being movable under control of the resistances to said different movements to effect the upwiping operation and the overwiping operation in a sequence determined by the shoe, and additional mechanism movable to vary the pressure of the wiping means on the shoe when it is over the shoe bottom.

39. In a lasting machine, the combination with lasting means mounted for movement in a direction heightwise of a shoe and also for movement in a direction transverse to the height of the shoe, of operating mechanism so constructed as to have a constant tendency in operation to impart movements in both said directions to the lasting means but controlled by the resistances to said movements to cause said means to move at any given time in the lasting operation in the direction in which the lesser resistance is encountered. 70

40. In a lasting machine, the combination with a lasting means mounted for movement in a direction heightwise of a shoe and also for movement in a direction transverse to the height of the shoe, of operating means comprising a member arranged to act through different trains of mechanism respectively to impart to said lasting means its movements in said different directions, said member being controlled by the resistance to the different movements of the lasting means to move said means at any given time in the lasting operation in the direction in which the lesser resistance is encountered. 75

41. In a lasting machine, the combination with a lasting means mounted for movement heightwise of a shoe toward the edge of the shoe bottom and also for movement in a direction transverse to the height of the shoe, of operating means comprising a lever arranged to act through different trains of mechanism respectively to impart to said lasting means its different movements, said lever being movable as determined by the resistances to the different movements of the lasting means to act through one train of mechanism or the other in accordance with which resistance is the smaller. 90

42. In a lasting machine, the combination with a lasting means mounted for movement heightwise of a shoe toward the edge of the shoe bottom and also for movement in a direction transverse to the height of the shoe, of operating means comprising a lever connected through different trains of mechanism to said lasting means to impart to said means its different movements, said lever being arranged to fulcrum about its connection with each train of mechanism to act on the lasting means through the other train of mechanism and being controlled in its movements by the resistances to the two movements of the lasting means. 100

43. In a lasting machine, the combination with a lasting means mounted for movement heightwise of a shoe toward the edge of the shoe bottom and also for movement in a direction transverse to the height of the shoe, of operating mechanism comprising a floating lever arranged to act at different portions of its length respectively to impart to said lasting means its different movements, and means 110

for applying force to said lever at another portion of its length to operate it.

44. In a lasting machine, the combination with a lasting means mounted for movement heightwise of a shoe toward the edge of the shoe bottom and also for movement in a direction transverse to the height of the shoe, of operating mechanism comprising a floating lever arranged to act at its opposite ends respectively to impart to said lasting means its different movements, and means for applying force to said lever between its ends to operate it.

In testimony whereof I have signed my name to this specification.

ARTHUR F. PYM.
